UNITED STATES PATENT OFFICE.

AUGUST VANDER LINDEN, OF HAYWARD, WISCONSIN.

VENTILATOR.

No. 919,193.

Specification of Letters Patent.

Patented April 20, 1909.

Application filed June 12, 1908. Serial No. 438,189.

To all whom it may concern:

Be it known that I, AUGUST VANDER LINDEN, a citizen of the United States, residing at Hayward, in the county of Sawyer and State of Wisconsin, have invented certain new and useful Improvements in Ventilators, of which the following is a specification, reference being had to the accompanying drawings.

My invention relates to improvements in 10 ventilating devices for use in windows.

The object of the invention is to provide a simple, inexpensive and practical device of this character which may be readily adjusted to fit windows of different widths and quickly 15 and easily applied to and removed from a window and which when not in use may be taken apart to permit it to be stored in a small space and easily shipped.

With the above and other objects in view, 20 as will hereinafter more fully appear, the invention consists of the novel features of construction and the combination and arrangement of parts, illustrated in the accompanying drawings, in which—

25 Figure 1 is a view of a portion of the inner side of a window having my improved ventilator arranged therein; Fig. 2 is a vertical transverse section through the window; Fig. 3 is a perspective view of the ventilator removed from the window; Fig. 4 is a detail perspective of one of the front or body sections of the ventilator; and Fig. 5 is a similar view of one of the end pieces or sections.

In the drawings 1 represents a portion of 30 an ordinary window frame having a sill 2 and a sash 3 slideable between stop or guide strips 4, 5.

35 My improved ventilator is adapted to be placed in the frame between its sill and the sash so as to permit of the entrance of fresh air into the room beneath the sash and at the same time effectively prevent rain, snow, and the like from entering the room. It comprises a front 6 and two ends 7, the front 40 being composed of slidably engaged sections 8, 9 so that the ventilator may be adjusted in width to accommodate different size window frames, and the ends 7 being detachably connected to the front sections 8, 9 to permit 45 the device to be readily taken apart and compactly folded when not in use. The front sections 8, 9 are in the form of metal plates 50 of rectangular shape and they are slidably connected by bending the upper and lower edges of one section 9 over upon themselves, as shown at 10, to provide guideways for the

upper and lower edges of the other section 8. The end sections 7 are also constructed of sheet metal and are triangular in shape, their detachable connection with the front sections 60 8, 9 being effected by bending their front edges upon themselves, as shown at 11, to receive similarly bent edges 12 of right angular flanges 13 formed on the ends of the front sections 8, 9. These slidably engaged edges 65 or flanges provide an interlocking connection for the sections 7, 8, 9 and permit them to be readily separated by sliding them apart. The rear or inner edges of the end sections 7 are bent outwardly at right angles to provide 70 flanges 14 adapted to be adjustably secured to supporting strips 15 by forming in said flanges 14 longitudinal slots 16 to receive clamping screws 17 arranged in the strips 15. The strips 15 and the flanges 14 are adapted 75 to enter the guideway in the window sash formed by the stop strips 4, 5 of the window frame and thereby retain the ventilator in position in the frame so that its end sections 80 7 are disposed vertically and its front section 6 is inclined upwardly and forwardly or inwardly. The adjustable connection between the supporting strips 15 and the end sections 7 is provided to permit the bottom edges of the front sections 8, 9 to project beneath the 85 plane of the upper face of the inner portion of the sill 2, as shown in Figs. 1 and 2 so as to effectively prevent rain or snow from beating into the room beneath the ventilator.

In order to more effectively retain the 90 ventilator in position with its flanges 14 and strips 15 between the stop strips 4, 5 of the frame I form in the upper edge of each of the end sections 7 above said strips 15 notches or seats 18 to receive the sash 3, which latter 95 may be supported in its open position by the strips 15 when it is not balanced by weights or otherwise supported.

In applying the ventilator to a window, the sash 3 is raised and the sections 8, 9 of 100 the front 6 are forced together so that the strips 15 and flanges 14 may be inserted beneath the sash, and the sections 8, 9 are then moved apart so that the strips 15 will be projected into the grooves or sash guide-way 105 formed by the stop strips 4, 5 of the frame. The sash may be then lowered to enter the notches 18 in the end pieces and rest upon the strips 15. By making the connection between the strips 15 and the end sections 7 110 of the ventilator adjustable the bottom edge of the front section 6 may be made to

project beneath the plane of the upper face of the inner portion of the sill and thereby prevent any rain or snow working into the room beneath said front section of the ventilator. By making the front section of slidably engaged sections it may be adjusted in width to accommodate windows of different widths and its flanges 14 and strips 15 may be readily engaged with and removed from the guideways of the window sash in applying and removing the ventilator. The slidable connection between the sections of the front in connection with the detachable interlocking engagement of the end sections with the front sections permits the device to be readily separated and compactly folded when not in use so that it may be stored in a small space and shipped or transported at a small expense. It will be further noted that the device is exceedingly simple in construction so that it may be produced at a small cost and will be strong and durable, and furthermore it is easy and convenient to adjust and to apply to and remove from a window. While I have shown and described in detail the preferred embodiment of my invention I wish it understood that I do not limit myself to the precise construction set forth and that various changes in the form, proportion and minor details may be resorted to without departing from the spirit or sacrificing any of the advantages of the invention.

Having thus described my invention what I claim is:

1. A window ventilator comprising slidably engaged front sections, removable end

sections disposed in planes at right angles to the front sections, a slidable interlocking connection between the edges of the front and end sections, the end sections being formed with slotted flanges, strips engaged with said flanges and adapted to enter between the stop strips of a window frame and fastenings passed through the slots in the flanges and into said strips, for the purpose set forth.

2. A window ventilator comprising an adjustable front section, end sections disposed at right angles to the front section and provided with outwardly projecting flanges having vertical slots, reinforcing strips arranged upon said flanges and adapted to enter between the stop strips of a window frame and fastenings passed through the slots in the flanges and into said strips, for the purpose set forth.

3. A window ventilator comprising an adjustable front section, substantially triangular-shaped end sections disposed at right angles to the front section, and an adjustable connection between the end and front sections, whereby the end sections may be removed from the front section when the device is not in use, said end sections being adapted to enter between the stop strips of a window frame.

In testimony whereof I hereunto affix my signature in the presence of two witnesses.

AUGUST VANDER LINDEN.
